PHOTOCELL AMPLIFIER

Application filed September 13, 1928, Serial No. 305,682. Renewed July 24, 1931.

Our invention relates to picture-transmission systems. More particularly, the invention relates to the circuits associated with a photo-electric cell for obtaining good representation of the changes in illumination of the cell by corresponding changes in electric currents.

In any picture-transmission system, the changes in illumination of the photo-electric cell, as the picture is traversed by the picture-exploring device, can never be absolutely abrupt. If the picture contains a perfectly sharp line separating a dark region from a bright region, the time required for the whole of the area commanded by the exploring device to travel across this boundary is finite, even when the boundary itself is a sharp line.

In any system of circuits usually associated with a photo-cell there are one or more conductive bodies connected to the photo-sensitive body in the cell and insulated from the rest of the system except for a high-resistance connection. These connected conductive bodies may be considered together as constituting one plate of a condenser. The opposite plate thereof will then include the "collector" or non-sensitive element in the photo-cell and the conductive bodies connected thereto. The discharge-path of the condenser is over said high resistance.

When the photo-cell is illuminated, the photo-electric surface and the conductors connected to it become charged by the departure of electrons under the influence of the light. When the photo-cell becomes dark, the quickest time in which this charge can be dissipated is the time during which the condenser, of which the photo-electric body and connected electrodes constitute one member, can discharge over the connecting resistance. Obviously, therefore, the smaller this resistance, the more rapid the discharge may be, and, therefore, the sharper the line in the reproduction of the picture, corresponding to any sharp line in the picture itself.

This resistance, however, must be fairly large because the potential drop across the resistor is the quantity which must be amplified to produce the electrical representa-

tion of the changes in illumination. For one purpose, a low resistance is desirable; for the other purpose, a high resistance is desirable.

It is an object of our invention to provide a means for meeting these seemingly irreconcilable requirements.

A picture, including a dark region and a bright region, separated by a sharp boundary, cannot be satisfactorily represented by the output of a photo-cell and an amplifier alone, because the amplifier will magnify only the change in current which occurs during the passage of the exploring area across the boundary. The steady condition representing the travel of the exploring area through the interior of one region will be exactly like that representing the interior of the other. Any usual amplifier can make no distinction between the two.

It is usual to avoid this difficulty by rendering the input to the amplifier periodic. The amplitude of the periodic current will be steady to represent travel of the exploring area through a uniformly illuminated region and will change when it passes into a differently illuminated region. One familiar way of doing this is to introduce a screen between the picture and the photo-cell. Every region is then crossed by a plurality of sharp lines of the screen, and the cell is intermittently illuminated when the exploring area travels through such region, even though the region be uniformly bright. A moving slotted mask between the picture and the cell has also been used for this purpose.

It is an object of our invention to provide a novel means for rendering the input to the amplifier periodic.

It is another object of our invention to employ the means for rendering the input periodic as a means for providing for the requirements of high resistance for some purposes and low resistance for others.

It is a further object of our invention to provide an intermittent shunt for the resistor associated with a photo-cell and to so choose the frequency of the intermissions that a satisfactory picture will be reproduced.

It is a further object of our invention to

provide means for preventing the frequency of said intermissions from impressing itself directly upon the input of the amplifier.

It is a further object of our invention to provide a system in which the above-mentioned condenser is periodically discharged and to so choose the period of duration of the discharge that the potential shall at no time correspond to a complete discharge and that the fall in potential during each discharge shall be relatively rapid.

It is a further object of our invention to control the potential of the condenser, which it has at the beginning of each discharge, by the illumination of the photo-cell.

Other objects of our invention and details of the construction will be understood from the following detailed description and the accompanying drawing, in which;

Fig. 1 is a diagram of the apparatus and circuits used in practicing our invention.

Fig. 2 is a modification of Fig. 1.

In Figure 1, the rectangular 1, marked "Variable Light Source" is intended to represent the exploring device by means of which the light from the picture to be transmitted is caused to vary in accordance with the brightness of the several points in the picture. Any usual or desired form of exploring device may be used. The particular exploring device chosen is not a feature of our invention.

Practically all such exploring devices receive light from a small area in the picture, and deliver it to the photo-cell. As the exploring device travels throughout the picture, the illumination of the photo-cell changes in accordance with the light received from the various points in the picture.

The varying light is delivered to the photo-cell 2 which is preferably of the gas-filled type. The photo-electric body 3 in the cell is connected to one terminal of a resistor 4. This resistor is preferably several megohms.

A high potential battery 5 is connected in series between the one end of the resistor 4 and the non-sensitive electrode of the photo-cell. A small battery 6 is inserted between the battery 5 and the resistor 4. The negative terminal of the battery 6 is connected to the resistor 4, and the positive terminal of the battery 5 is connected to the photo-cell. It will, therefore, be apparent that, if desired, the battery 6 may be a small portion of the battery 5, but it is ordinarily more convenient to have separate batteries.

The terminal of the resistor 4, which is connected to the element 3, is also connected to the anode 7 of a vacuum tube 8. The cathode of the vacuum tube may be of the ordinary type, or, if preferred, may be an indirectly heated cathode. The heater 10 is shown as energized from a source of alternating current represented by the transformer 11.

The transformer 11 is also used to supply heating energy to the heater 12 of the cathode 13 of a second vacuum tube 14. The vacuum tube 8 is provided with a second grid shown as a screen-grid 15 surrounding the anode 7. A battery 17 is provided which places a strong positive potential upon the screen grid 15. Preferably, the grid 15 is in the form of two cylindrical sheets of wire mesh, one inside and one outside of the cylindrical anode 7, but this specific form is not essential.

The grid 20, which is next to the cathode 9 of the tube 8 serves to control the space current in said tube. A small negative bias is placed upon this grid by a battery 21. Superposed upon the biasing potential is an alternating potential which is represented as impressed through the transformer 22 from a source 23 of moderately high frequency.

The tube 14 is provided with a grid 25 which is connected to the plate 7, the resistor 4 and to the photo-electric member 3 of the cell 2. The tube 14 is also provided with an anode 26. Connections from the anode 26 and the cathode 13 constitute the output circuit of the tube 14. The output circuit includes the usual B battery, not explicitly shown on the drawing but included in the rectangle 27, marked "Amplifier". The amplifier 27 may comprise as many vacuum tubes as necessary. The tube 14 is also provided with a screen-grid 28 biased positively by a battery 29, in a way closely similar to the screen grid 15 and battery 17 in the tube 8.

The amplifier 27 is connected to the modulator of a system represented by the rectangle 31 and including any usual or desired transmitting device, whereby modulated carrier currents are delivered to the antenna 32 and thus transmitted to the receiving station.

In the operation of the device, if the photo-electric cell 2 is uniformly illuminated, the metallic body, comprising the photo-sensitive member 3, the anode 7 and the grid 25, will tend to become positively charged. This tendency will be offset by the current through the resistor 4 which tends to bring the potential of said metallic body to a value nearly the same as the negative terminal of the battery 6.

The potential resulting from the two tendencies will persist as long as the tube 8 is not conductive. The period during which the tube 8 is non-conducting is determined by the period of the generator 23. The potential of the battery 21 impresses a small negative bias upon the grid 20 preferably such as to render the tube 8 non-conductive when no potential is impressed upon the grid 20 from the transformer 22. Even when the anode 7 receives a negative potential from the battery 6, the tube 8 will be slightly conducting because of the effect of the large

positive potential upon the screen-grid 15. The bias supplied by the battery 21 should be sufficient to overcome this. The potential from the secondary 22 will produce a nearly proportional change in the conductivity of the tube 8 when it renders the grid 20 more positive, but when the transformer 22 delivers a negative potential to the grid 20, the tube 8 becomes absolutely non-conductive.

10 The frequency of the generator 23 is chosen to correspond to the faithfulness with which the reproduction shall give the details of the original picture. Thus, if the time required for the exploring area to cross a sharp line in the picture is known, the period of the generator 23 should be less than this. We have found that it is sufficient if the period is not greater than one-half of said time. For the transfer of pictures with a satisfactory degree of detail, it is found that 3,000 cycles per second is sufficient frequency for the generator 23.

15 When the tube 8 becomes conductive, the positive charge which has accumulated upon the anode 7, grid 25 and photo-sensitive member 3 tends to discharge through the tube 8. This is in addition to the steady discharge current in the resistor 4. Consequently, the potentials of the anode 7 and the grid 25 20 decrease.

25 The manner in which the potential varies with the time during this discharge is well represented by the familiar curve for the discharge of a condenser through a high resistance. That is to say, the decrease of potential is at first very rapid, but afterward it diminishes more slowly. The time during which the potential of such condenser will decrease to

$$40 \quad \frac{1}{e}$$

of the original value, where e is the Naperian base, is called the capacitative time-constant.

45 In order to avoid being obliged to wait until the discharge is substantially complete, the frequency of the generator 23 is made so high that the tube 8 becomes non-conducting again while the rate of discharge of the capacitative system is still large. Preferably, the time during which the tube 8 is conductive is made smaller than the capacitative time-constant of the system including the capacity of the photo-cell, the grid-cathode capacities of tubes 8 and 14 and the combined impedance of resistor 4 and tube 8 in parallel. In this way, the changes in potential on the grid 25 are rapid and the magnitude of them is governed, not by the constant amplitude of the potential from the transformer 22, but by the potential which is impressed upon the anode 7 and this is dependent upon the degree of illumination of the photo-cell 2.

50 55 60 65 70 75 80 85 90 95 100 105 110 115 120 125 130 While illumination of the photo-cell 2 is

steady, a steady current from the battery 5 flows through the photo-cell and through the resistor 4. Except for the permanent effect of the battery 6, which, under these conditions, is small, the potential impressed across the vacuum tube 8, to operate as a B battery for said tube, is the drop over the resistor 4. The fluctuations in the potential of the grid 20 produce fluctuations in the potential of the plate 7 which are a function of the B battery potential impressed on this tube, that is, they are dependent upon the steady drop over the resistor 4 just mentioned.

70 75 80 85 90 95 100 105 110 115 120 125 130 When the photo-cell 2 is highly illuminated, the cell is conductive. The current through the resistor 4 is, therefore, large. The drop over this resistor is large and the B battery potential for the tube 8 is large. Consequently, the amplitude of the potential at the plate 7, and therefore, the amplitude of the potential on the grid 25, is larger than when the photo-cell 2 is but faintly illuminated.

90 95 100 105 110 115 120 125 130 The output of the vacuum tube 14 is, therefore, an alternating current of the frequency of the generator 23 and of an amplitude determined by the illumination of the photo-cell 2. The output is not, however, of the usual sine-wave form. It consists of steep parts corresponding to the rapid but partial discharge of the condenser, including members 3, 7 and 25, and then a rapid charging thereof. The potential to which it is charged each time is fixed by the illumination. The potential to which it discharges, being a fraction of the potential when charged, which fraction is determined by the time the tube 8 remains conductive, is also, though to a smaller degree, variable with the illumination of the photo-cell.

100 105 110 115 120 125 130 The picture corresponding to variations in the light source 1 is thus represented in the energy delivered from the antenna 32 by a modulation having a high frequency and an amplitude determined by the brightness of that point in the picture represented by the transmitting energy at any particular instant.

110 115 120 125 130 When the photo-cell 2 is completely dark, the potential of the end of the resistor 4, connected to the photo-cell, will be the potential of the negative terminal of the battery 6, because this battery is then connected to no closed circuit. The battery 6 is preferably of a potential to impress upon the grid 25 a bias which will bring the tube 14 to the condition corresponding to the lower end of the straight part of the grid-potential-plate-current characteristic. Small fluctuations in the plate current from the tube 14 result from the potential impressed by the secondary 22 upon the grid 20 in the tube 8 while the photo-cell 2 is dark.

130 The means for synchronizing the sending and receiving stations requires a special modulation of the output from the antenna 32

at each traverse of the picture. The means for producing this is not shown because it does not constitute a part of the invention covered by this application. This means impresses upon the grid 25 a sufficiently negative potential to completely cut off the plate current. The amplifier 27 thus delivers no current to the modulator constituting a part of the apparatus 31, and the output from the 10 antenna 32 will be completely unmodulated when transmitting the synchronizing control.

Similarly, when the illumination of the photo-cell 2 is a maximum, the current applied by the battery 5 is a maximum, the drop 15 across the resistor 4 is a maximum, the B-battery voltage for the tube 8 is a maximum and, consequently, the periodic potential at the anode 7 is a maximum. This produces maximum change of potential at the grid 25 which, 20 being amplified, produces maximum modulation of the energy delivered to the antenna 32.

Even when the periodic changes on the anode 7 are a maximum, they are without effect across the capacity between the anode 7 25 and the grid 20, or between the anode 7 and the cathode 9. They, therefore, produce no direct effect, through any capacity, upon the grid 25. The reason for this is that the screen-grid 15 is so strongly positive that no 30 potential changes on the anode 7 exert an influence beyond the screen grid. The potential changes upon the grid 20 can, therefore, produce a result upon the grid 25 only as they act through the space-current effect in the 35 tube 8.

This is ordinarily an amplifying effect, but it may, when the potential across the resistor 4 is small enough, be a de-amplifying effect. By a de-amplifying effect we mean that the 40 change in the plate current is less than the change of potential upon the grid. It has already been pointed out that when the photo-cell is dark, the potential between the anode 7 and the cathode 9 is determined by 45 the battery 6 and this may, if desired, be so small that the changes in plate current are small.

It is, for some purposes, advantageous to 50 separate the grid 25 from the anode 7 by a condenser 33 as in Fig. 2. When this is done, a resistor 34 and a biasing battery 35 should be inserted to connect the grid 25 with the cathode 13. Under these circumstances, the biasing battery 6 may be omitted. The drop 55 across the resistor 4 will then be only that due to the very small current which flows by leakage through the photo-cell 2 when it is dark.

Many variations in the details of the construction will readily occur to those skilled 60 in the art. The specific description of but one form of our invention is therefore not to be considered as a limitation. No limitation is intended except such as is required by the 65 prior art or indicated in the following claims.

We claim as our invention:

1. In combination, a photo-cell, a resistor connected between the electrodes of said photo-cell, a vacuum tube the space-current path of which is connected in shunt to said resistor, and means for changing the condition of said vacuum tube between conducting and non-conducting at high frequency. 70

2. In combination, a photo-cell, a resistor connected between the electrodes of said photo-cell, a vacuum tube in shunt to said resistor, means for changing the condition of said vacuum tube between conducting and non-conducting at high frequency, means for amplifying the changes in potential across 75 said resistor, and means for preventing said high frequency from being impressed by direct electrostatic action upon said amplifying means.

3. In combination, space-current devices, certain members thereof forming a capacitive system, one of said devices being photo-electrically controlled and determining the potential of said system, an impedance over 80 which said system may discharge, means for periodically rendering said impedance non-conducting, the duration of the conductive period being less than the capacitive time-constant. 90

4. In a picture-transmitting apparatus, a vacuum tube, means for impressing a periodic potential upon the grid thereof and means for impressing between the anode and the cathode thereof a potential controlled by a light-responsive device. 95

5. In a picture-transmission system, a conductive body forming one member of a capacitative system, a high resistance discharge path for said system and means for providing an auxiliary discharge path of varying conductivity. 100

6. In a picture-transmission system, a conductive body forming one member of a capacitative system, a high resistance discharge path for said system and means for providing an auxiliary discharge path of varying conductivity, the period during which said auxiliary discharge path is of substantial conductivity being less than the capacitative time-constant of said capacitative system. 105

7. In combination, a photo-cell, a resistor connected between the electrodes of said cell, a vacuum tube the space-current path of which is connected in shunt to said resistor, means for changing the condition of said vacuum tube between conducting and non-conducting at high frequency, and means for amplifying changes in potential across 110 said resistor.

8. In combination, a photo-cell, a resistor connected between the electrodes of said cell, a vacuum tube having an input circuit including said resistor, a second vacuum tube the space-current path of which is connected in shunt to said resistor, and means for 115 120 125

changing the condition of said second vacuum tube between conducting and non-conducting at high frequency.

9. In combination, a photo-cell, a resistor connected between the electrodes of said cell, a vacuum tube having an input circuit including said resistor, a second vacuum tube of the shield-grid type the space-current path of which is connected in shunt to said resistor, means for rapidly changing the condition of said second vacuum tube between conducting and non-conducting, and means for biasing the shield grid thereof to a potential sufficiently positive to prevent changes in the plate potential from appearing as variations in the output current therefrom.

10. In combination, a photo-cell, a resistor connected between the electrodes of said cell, a vacuum-tube amplifier having an input circuit including said resistor, a potential source in series with said photo-cell and said resistor, a potential source for biasing said amplifier to the cut-off point, a vacuum tube the space-current path of which is connected in shunt to said resistor, and means for changing the condition of the last mentioned vacuum tube between conductive and non-conductive at high frequency.

In testimony whereof, we have hereunto subscribed our names this 14th day of August, 1928.

VLADIMIR K. ZWORYKIN.
HARLEY A. IAMS.
